CLAIM

The ornamental design for a body-worn electronic device with display, as shown and described.

DESCRIPTION

FIG. 1 is a top, front perspective view of a body-worn electronic device with display according to the present invention;

FIG. 2 is a top, rear perspective view of the body-worn electronic device with display;

FIG. 3 is a front view of the body-worn electronic device with display;

FIG. 4 is a rear view of the body-worn electronic device with display;

FIG. 5 is a left side view of the body-worn electronic device with display;

FIG. 6 is a right side view of the body-worn electronic device with display;

FIG. 7 is a top view of the body-worn electronic device with display; and,

FIG. 8 is a bottom view of the body-worn electronic device with display.

The broken lines shown in the drawings represent portions of the body-worn electronic device with display that form no part of the claimed design.
